(57) **CLAIM**

The ornamental design for a product container with integrated carry handle, as shown and described.

DESCRIPTION

FIG. 1 is a perspective view of the top, front and right sides of a product container with integrated carry handle in accordance with one embodiment of my new design, the top, front and left side perspective view being a mirror image thereof;

FIG. 2 is a right-side elevational view of the product container with integrated carry handle in accordance with the new design;

FIG. 3 is a left-side elevational view of the product container with integrated carry handle in accordance with the new design;

FIG. 4 is a front elevational view of the product container with integrated carry handle in accordance with the new design;

FIG. 5 is a rear elevational view of the product container with integrated carry handle in accordance with the new design;

FIG. 6 is a top plan view of the product container with integrated carry handle in accordance with the new design;

FIG. 7 is a bottom plan view of the product container with integrated carry handle in accordance with the new design;

FIG. 8 is a perspective view of the top, front and right sides of the product container with integrated handle of FIG. 1, wherein the top side is depicted in an open configuration in accordance with the new design;

FIG. 9 is a left-side elevational view of the product container with integrated carry handle, wherein the container is depicted in an open configuration in accordance with the new design;

FIG. 10 is a right-side elevational view of the product container with integrated carry handle, wherein the container is depicted in an open configuration in accordance with the new design;

FIG. 11 is a front elevational view of the product container with integrated carry handle, wherein the container is depicted in an open configuration in accordance with the new design;

FIG. 12 is a rear elevational view of the product container with integrated carry handle, wherein the container is depicted in an open configuration in accordance with the new design;

FIG. 13 is a top plan view of the product container with integrated carry handle, wherein the container is depicted in an open configuration showing the interior side of the bottom plan view of FIG. 7 of the container in accordance with the new design; and,

FIG. 14 is a bottom plan view of the product container with integrated carry handle, wherein the top of the container is depicted in an open configuration in accordance with the new design.

The broken lines in FIG. 13 represent unclaimed portions of the design.
